(57) CLAIM

The ornamental design for a sweater pattern, as shown and described.

DESCRIPTION

FIG. 1 is a front view of a sweater pattern showing my new design;

FIG. 2 is a rear view thereof, the ornamentation on the folded arm of the sweater being the same as that on the extended arm;

FIG. 3 is an enlarged detailed view of the front panel of FIG. 1; and,

FIG. 4 is an enlarged detailed view of the rear panel of FIG. 2.

The broken lines are for illustrative purposes only and form no part of the claimed design.

1 Claim, 4 Drawing Sheets

FIG. 4
